CLAIM

The ornamental design for a golf club head, as shown and described.

DESCRIPTION

FIG. 1 is a rear elevation view of a golf club head;
 FIG. 2 is a front elevation view thereof;
 FIG. 3 is a top plan view thereof;
 FIG. 4 is a bottom plan view thereof;
 FIG. 5 is a toe-side elevation view thereof;
 FIG. 6 is a heel-side elevation view thereof;
 FIG. 7 is a top perspective view thereof; and,
 FIG. 8 is a top perspective view of the golf club head connected to a shaft in broken lines.
 The broken lines shown in the drawings form no part of the claimed design.
